COMPRESSOR SHUT-OFF VALVE
MECHANISMCyril B. Fites, Ferguson, Mo., assignor to Wagner
Electric Corporation, St. Louis, Mo., a corpora-
tion of Delaware

Application July 11, 1938, Serial No. 218,531

7 Claims. (CL 363—11)

My invention relates to valve mechanism and more particularly to shut-off valve mechanism for unloading a compressor under certain conditions. The valve mechanism embodying my invention is an improvement in the valve mechanism shown in the application of Fred H. Stroup, Serial No. 217,484, filed July 5, 1938.

One of the objects of my invention is to provide an improved valve mechanism for cutting off the intake of the compressor when the pressure in the compressor receiver is a predetermined value and for again permitting operation of the compressor whenever fluid under pressure is used from the compressor by a fluid pressure-actuated system associated therewith or whenever the pressure in the receiver drops to a predetermined minimum value during a period when the fluid pressure-actuated system is not operated.

Another object of my invention is to so construct and arrange the parts of the valve mechanism that an efficient operating valve is produced which will shut off and open the compressor intake at the desired time.

Other objects of my invention will become apparent from the following description taken in connection with the accompanying drawing in which Figure 1 is a view showing my improved valve mechanism associated with a fluid compressor and a fluid pressure-actuated system; and Figure 2 is a longitudinal cross-sectional view of the valve mechanism showing the details thereof; and Fig. 3 is a view on the line 3—3 of Fig. 2.

Referring to the drawing in detail, the air compressor 1, with which I have illustrated my shut-off valve mechanism as being associated, is of the rotary type having a stator 2 and an eccentrically mounted rotor 3 provided with a plurality of blades 4 (one only being shown). The stator 2 has an intake port 5 and an outlet port 6, the latter opening into an oil dome 7 which is connected to a pressure tank 8 by means of a conduit 9, the dome and tank both being considered the receiver of the compressor. The outlet of the compressor has associated therewith a check valve 10 for preventing back flow of compressed fluid and associated with the outlet of the dome is another check valve 11. The pressure tank 8 is shown as connected by a conduit 12 with a fluid motor 13 which may be employed to operate any mechanism desired, as for example, a braking mechanism. The fluid pressure employed to actuate the fluid motor is controlled by a valve 14 in conduit 12, this valve being shown as a hand valve but it is understood that other valve

mechanisms such as a foot control valve may be employed if desired.

In compressors of the type described which are of well-known construction it is desirable to automatically prevent the compressor from compressing fluid after the fluid in the receiver has been placed under a predetermined maximum pressure. This is best accomplished by shutting off the intake port so the air or other fluid which is being compressed by the compressor is not permitted to enter the compressing chamber. It is also desirable that the intake port not only be automatically closed at the proper time but that it also be reopened whenever the pressure in the receiver drops to a predetermined value below the said maximum.

In accordance with my invention I have provided an improved valve mechanism 15 which is associated with the compressor intake and also the compressor oil dome and the fluid pressure system connected to the pressure tank whereby the desired opening and closing of the compressor intake is accomplished. The valve mechanism comprises connected casings 16 and 17, the former being provided with a bore 18 and the latter with two bores 19 and 20. The casing 16 is formed with an outlet 21 communicating with the intake port 5 of the compressor when the valve mechanism is mounted on the compressor and there is also provided an inlet port 22 (Figure 3) which is associated with a suitable air cleaner 23. Between outlet 21 and inlet 22 the casing is formed with a valve seat 24 which cooperates with a slidable valve member 25 positioned in bore 18 and normally biased off its seat by a spring 26 interposed between the valve member and the end of the casing. The valve member carries on one end an annular rubber element 27 to facilitate tight fitting of the valve member with the seat. There is also a packing cup 28 at the other end of the valve member to prevent leakage of fluid past said member.

The valve casing 17 is secured to valve casing 16 by suitable bolts 29 (Figure 1) so that bore 19 is in alignment with bore 18 of valve casing 16. The bore 18 communicates by means of a passage 30 with a chamber 31 at the rear of the valve member 25. This passage is normally closed by a valve element 32 preventing flow of fluid from chamber 31 to bore 19. Within bore 19 is a piston 33 carrying the valve element 32 by a stem 34, the piston being biased by a spring 35 to a position normally holding valve element 32 seated. The piston also carries a valve element 36 which is adapted to close passage 30.

when the piston is moved to the left and the valve element 32 is unseated. The bore 19 at the left of the piston is in communication with the atmosphere by a bleed passage 37. A packing element 38 seals the piston 33 and the right end of the bore is connected by a conduit 39 with conduit 12 at a point between the control valve 14 and the fluid motor 13.

Within bore 20 of casing 17 is a diaphragm 40 which is normally held upon a seat 41 by a plunger 42 and spring 43. The diaphragm and seat form a valve to prevent communication between an inlet passage 44 connected to the compressor oil dome port of the receiver by a conduit 45 and a passage 46 leading to chamber 31 at the rear of valve member 25.

The spring 43 is so designed as to hold the diaphragm against seat 41 until a predetermined pressure is built up in the oil dome and also the pressure tank, which pressure is the maximum pressure desired for the receiver. When the diaphragm is unseated, a larger area will be exposed to maintain it in this position. The spring 43 will reseat the diaphragm against the pressure in the tank when this pressure drops to a value of about ten pounds per square inch below the maximum tank pressure. For the purposes of description of the operation of the valve mechanism, the maximum pressure is considered as one hundred pounds per square inch. The spring 26 which biases the valve member to open position is also so designed that it will unseat valve member 25 against the maximum suction effect of the compressor and also permit valve member 25 to engage seat 24 when fluid pressure is admitted to chamber 31 as a result of the diaphragm 40 being moved off its seat when the pressure in the receiver is one hundred pounds per square inch.

40 When the valve parts are in the position shown air is free to enter the compressor and then be forced out into the oil dome and the tank. When the pressure in the oil dome and tank reaches the maximum pressure of one hundred pounds per square inch, the diaphragm 40 will be moved off its seat, thereby permitting fluid under pressure to flow through passage 46 into chamber 31. This pressure will now move valve member 25 against its spring 26 to close off communication 45 to the compressor, causing it to run idle. If the control valve 14 should be moved to a position to cause operation of the fluid motor 13, air under pressure will be admitted to conduit 39 and become effective on piston 33 to move it to the left, thereby unseating valve 32 and seating valve 36. During the short interval that the passage 30 is open, the chamber 31 is connected to atmosphere and the pressure in the chamber may drop sufficiently to cause the valve member 25 to be unseated by the action of its spring 24. However, as soon as valve element 36 becomes seated, the chamber will be again closed and pressure from the tank will cause the valve member 25 to be quickly reseated.

65 If operation of the fluid motor causes the air pressure in tank 8 to drop more than ten pounds per square inch, the diaphragm 40 will be forced onto its seat 41 by spring 43 so that fluid under pressure no longer can enter chamber 31. When 70 the control valve 14 exhausts the fluid pressure in the fluid motor, fluid pressure acting on piston 33 will also be exhausted and the piston, under the action of the light spring 35, will be forced to the right, first unseating valve element 36 and then, after a short interval, reseating valve ele-

ment 32. During this short interval between the unseating of valve element 36 and reseating of valve element 32, the chamber 31 will be in communication with the atmosphere by way of passages 30 and 37, thereby relieving the high pressure in chamber 31. The amount of fluid to be exhausted from chamber 31 is very small and although the interval between the unseating of valve element 36 and reseating of valve element 32 may be short, passageway 30 is, nevertheless, 10 open long enough to permit a substantial drop in the pressure of the fluid in the chamber 31. Furthermore, the fluid pressure acting on piston 33 will never be exhausted quickly due to the fact that it must pass back through pipe 39 and 15 out through the control valve 14 along with the fluid being exhausted from the fluid motor 13 and this will also aid maintaining the passage 30 open long enough to cause a sufficient drop in pressure in chamber 31. The drop in pressure 20 in the chamber permits spring 26 to force the valve member 25 away from seat 24 and again allow air to flow to the intake of the compressor. The compressor will now operate until the one hundred pounds per square inch pressure in the 25 dome and tank is reached when the valve member will again close off the compressor intake in a manner already described.

If during operation of the fluid motor 13 the drop in air pressure in the tank 8 is less than 30 ten pounds per square inch, then the diaphragm 40 will not be seated by the action of spring 43 and chamber 31 will not be disconnected from the air tank. Under these conditions when the control valve 14 exhausts the pressure in the fluid 35 motor, the air pressure in chamber 31 will be relieved to atmosphere during the unseating of valve element 36 and the reseating of valve element 32 and possibly some fluid will also escape from the air tank due to the diaphragm 40 being 40 unseated. The drop in pressure in chamber 31 will be sufficient to permit the spring 26 to move valve 25 off seat 24 and open the intake of the compressor. However, as soon as valve 32 becomes seated, fluid under pressure will again be 45 built up in chamber 31 and the valve element 25 reseated. This momentary opening and reclosing of the intake valve, however, does not interfere with the desired operation of the valve control mechanism and the maintaining of the pressure in tank 8 within predetermined limits.

In order to insure that the air pressure in chamber 31 will be sufficiently released to allow valve member 25 to be unseated by spring 26, there is provided a small bleed passage 47 through the valve member which in the construction shown is approximately one forty-thousandths of an inch in diameter. This small bleed passage will not affect the closing action of the valve member since it is of such size that pressure can be built up in chamber 31 to move the valve member. After the valve member has become seated what little leakage of fluid takes place through the bleed passage enters into the intake of the compressor and is again placed in 60 the dome.

In the event there should be a leak in the compressor dome or the tank which may cause a drop in the pressure in the dome or tank or both while the compressor is shut off and during the period 70 that the fluid motor 13 is not operated, the valve mechanism, nevertheless, will function to open the intake of the compressor. For example, if the drop should be ten pounds per square inch, this would be sufficient to permit diaphragm 40 75

to engage seat 41. No additional pressure will now be placed in chamber 31 and, therefore, the pressure therein will drop because of bleed passage 47. When the pressure in chamber 31 drops to such a value that the spring can move valve element 25 to open position, the compressor will again begin to operate and bring the pressure in the dome and the tank up to its maximum value at which point the valve mechanism will again be operated to shut off the compressor.

Being aware of the possibility of modifications in the particular structure herein described without departing from the fundamental principles of my invention, I do not intend that its scope be limited except as set forth by the appended claims.

Having fully described my invention, what I claim as new and desire to secure by Letters Patent of the United States is:

1. In apparatus of the class described, a fluid compressor provided with an intake port and an exhaust port, a fluid pressure receiver connected to the exhaust port, a fluid pressure-actuated system adapted to be operated by fluid pressure from the receiver, a casing having a passage in communication with the intake port, a chamber in the casing, a movable valve member in the chamber and adapted to control the passage, a spring for biasing the valve member to open position, conduit means for connecting the chamber to the receiver, pressure-operated valve means for permitting fluid to flow to the chamber when the pressure in the receiver is a predetermined value, means forming a relief passage from the chamber, and valve means independent of the pressure-operated valve means and operable by fluid pressure from the fluid-actuating system for causing a release of the fluid under pressure in the chamber.

2. In apparatus of the class described, a fluid compressor provided with an intake port and an exhaust port, a fluid pressure receiver connected to the exhaust port, a fluid pressure-actuated system adapted to be operated by fluid pressure from the receiver, a casing having a passage in communication with the intake port, a chamber in the casing, a movable valve member in the chamber and adapted to control the passage, a spring for biasing the valve member to open position, conduit means for connecting the chamber to the receiver, pressure-operated valve means for permitting fluid to flow to the chamber when the pressure in the receiver is a predetermined value, means forming a relief passage from the chamber, and spring-biased valve means operable by fluid pressure from the fluid pressure-actuated system for controlling said valve means, said valve means being so associated with the relief passage that operation thereof by fluid pressure will first open the passage then close it and release of the pressure will permit reopening of the passage and then a closing thereof under the action of the spring.

3. In apparatus of the class described, a fluid compressor provided with an intake port and an exhaust port, a fluid pressure receiver connected to the exhaust port, a fluid pressure-actuated system adapted to be operated by fluid pressure from the receiver, a casing having a passage in communication with the intake port, a chamber in the casing, a movable valve member in the chamber and adapted to control the passage, a spring for biasing the valve member to open position, conduit means for connecting the chamber to the receiver, pressure-operated valve means

for permitting fluid to flow to the chamber when the pressure in the receiver is a predetermined value, and means forming a restricted relief passage through the movable valve member and placing the chamber in constant communication with the portion of the passage in the casing which constantly communicates with the intake when the passage is closed.

4. In apparatus of the class described, a fluid compressor provided with an intake port and an exhaust port, a fluid pressure receiver connected to the exhaust port, a casing having a passage in communication with the intake port, a chamber in the casing, a movable valve member in the chamber and adapted to control the passage, a spring for biasing the valve member to open position, conduit means for connecting the chamber to the receiver, and pressure-operated valve means for permitting fluid to flow to the chamber when the pressure in the receiver is a predetermined value, said valve means comprising a seat associated with the conduit means, a flexible diaphragm and a spring member for biasing the diaphragm against the seat, and means including a restricted passage for placing the chamber in communication with the intake only of the compressor when the valve member is in closed position.

5. In apparatus of the class described, a fluid compressor provided with an intake port and an exhaust port, a fluid pressure receiver connected to the exhaust port, a casing having a passage in communication with the intake port, a chamber in the casing, a movable valve member in the chamber and adapted to control the passage, a spring for biasing the valve member to open position, conduit means for connecting the chamber to the receiver, pressure-operated valve means for permitting fluid to flow to the chamber when the pressure in the receiver is a predetermined value, said valve means comprising a seat associated with the conduit means, a flexible diaphragm and a spring member for biasing the diaphragm against the seat, and means for relieving the pressure in the chamber.

6. In apparatus of the class described, a fluid compressor provided with an intake port and an exhaust port, a fluid pressure receiver connected to the exhaust port, a fluid pressure-actuated system adapted to be operated by fluid pressure from the receiver, a casing structure having two communicating aligned bores and a third bore, means including a portion of one of the aligned bores for forming a passage communicating with the intake of the compressor, a movable valve member in said last named bore for controlling the passage, a spring for biasing the valve member to open position, conduit means for placing the third bore in communication with the bore having the movable valve member and at a point to the rear thereof, means for connecting the third bore with the receiver, valve means associated with the third bore for preventing fluid under pressure from acting on the movable valve member except when the pressure in the receiver is above a predetermined value, valve means for controlling communication between the aligned bores, and means operable by fluid pressure in the fluid pressure-actuated system for actuating the last named valve means and comprising a movable member in the other of the aligned bores.

7. In apparatus of the class described, a fluid compressor provided with an intake port and an exhaust port, a fluid pressure receiver connected to the exhaust port, a fluid pressure-actuated system

- ated system adapted to be operated by fluid pressure from the receiver, a casing having a passage in communication with the intake port, a chamber in the casing, a movable valve member in the chamber and adapted to control the passage, a spring for biasing the valve member to open position, conduit means for connecting the chamber to the receiver, means forming a relief passage from the chamber, valve means for controlling the relief passage and comprising a movable member having a valve stem carrying spaced valve
- 5
- 10

elements, a spring for biasing one of said valve elements to closed position and the other to open position, means operable by fluid pressure from the fluid-pressure-actuated system for moving said valve elements against the spring to thereby move the first valve element to open position and the other to closed position, and means associated with the valve elements and the spring for causing said valve elements to have a delayed movement to their first mentioned positions.

CYRIL B. FITES.
